UNITED STATES PATENT OFFICE.

MATO F. MA LONEY, OF ATLANTIC BEACH, FLORIDA.

DESIGN FOR A HAT-HOLDER.

51,018.

Specification for Design.

Patented July 10, 1917.

Application filed February 1, 1917. Serial No. 146,041. Term of patent 14 years.

To all whom it may concern:

Be it known that I, MATO F. MA LONEY, a citizen of the United States, residing at Atlantic Beach, in the county of Duval, State of Florida, have invented a new, original, and ornamental Design for Hat-Holders, of which the following is a specification, reference being had to the accompanying drawing, forming part thereof, and wherein—

Fig. 2 is a side view thereof; and
Fig. 3 is a front view.

I claim:

The ornamental design for a hat holder as shown.

MATO F. MA LONEY.

Witnesses:

G. J. AVENT,
I. J. WHITCOMB.
